UNITED STATES PATENT OFFICE.

MOSES M. KAHN, OF SAN FRANCISCO, AND FRANKLYN J. SILVA, OF OAKLAND, CALIFORNIA; SAID SILVA ASSIGNOR TO MOSES M. KAHN.

DUMP-BODY PARTITION AND OPERATING MEANS THEREFOR.

1,376,146.

Specification of Letters Patent. Patented Apr. 26, 1921.

Application filed May 26, 1920. Serial No. 384,303.

To all whom it may concern:

Be it known that we, MOSES M. KAHN and FRANKLYN J. SILVA, citizens of the United States, residing at San Francisco, in the 5 county of San Francisco, and Oakland, in the county of Alameda and State of California, respectively, have invented new and useful Improvements in Dump-Body Partitions and Operating Means Therefor, of 10 which the following is a specification.

This invention relates to dump body partitions and operating means therefor.

When emptying auto trucks or other transporting means equipped with dump bodies for transferring materials of various kinds such as used in road construction and the like, it is often desirable that the contents of the body be dumped in several separate and equal quantities for the 20 purpose of mixing the different materials or for the purpose of distribution thereof. With this in view the present invention consists in employing partitions for dump bodies and thus dividing the body into several 25 separate compartments of the same capacity. Also the invention consists in mounting the partitions for swinging movement so as to permit the material to escape from the compartments when the body is in 30 its inclined or dumping position. Means are provided for locking the partitions in their closed or transverse position with relation to the body and also means for releasing said partitions for individually 35 dumping the contents of each compartment.

It is an object of the invention that the partitions are easily detachable and that when removed the body will not be impaired in any way for use in other hauling 40 purposes.

Another object of the invention is to provide means for operating the partitions when dumping that one man can easily manipulate.

Also it is a general object of the invention that the operating means for locking and releasing the partitions shall be simple in construction and positive in operation.

Other objects and objects relating to details of construction will hereinafter appear in the detailed description to follow.

The invention is illustrated in the accompanying drawings in which:

Figure 1 is a side elevation of a truck having a dump body and showing in dotted 55 lines the body in its inclined position for dumping.

Fig. 2 is a transverse section of the body.

Referring to the drawings more particularly—Fig. 1 illustrates an auto truck 60 equipped with a dump body which is generally indicated by "A". The body is of the conventional type having a tail gate 10 and sides 11. A front board closes the forward end of the body in the usual manner. 65 Transversely of the body and in equally spaced relation are mounted the partitions 12, in this instance three partitions, which divide the body into four equal compartments. Of course it is to be understood 70 that any number of partitions could be employed, depending upon the capacity of each compartment desired. The partitions may be of any shape but preferably as shown in Fig. 2. On each partition, longitudinally 75 thereof, there is secured by rivets or the like, an angle iron 13 and at one end thereof there is secured a trunnion 14, while on the other end of each angle iron there is likewise secured a trunnion 15, the trunnions 80 15 having an extended portion 16 which is squared as shown. The trunnions for each partition are journaled in a pair of bearings 17 whereby the partitions are permitted a swinging movement. The bearings are 85 secured to the upper edges of the sides of the body by screw bolts 18 or the like, and, as is obvious, by taking out the screw bolts the partitions, as a whole, together with the trunnions and bearings can easily be lifted 90 from the body. On each squared end portion of the trunnions 15 there is rigidly secured one end of an arm 19, the other ends of the arm 19 are bifurcated as at 20. On the same side of the dump body there are 95 mounted controlling rods 22 one for each partition. These rods are journaled in angle irons 23 which are riveted or otherwise secured to the side of the body. The forward end of each rod 22 has secured thereon 100 a member 24 which extends at right angles to the rod and adapted to project into

- the bifurcated end of an arm 19 with which the rod is associated. As is apparent, this locks the arms 19 against movement and thus the partitions 12 are likewise rigidly held in their closed or transverse positions with respect to the body "A". These locking members 24 are bolted to the ends of the rods so that they may be easily removed in case it is so desired.
- 10 A rear end portion 25 of each rod 22 is bent substantially at right angles to the rods and also these portions extend at substantially right angles to the locking members 24 on the forward ends of the rods. The 15 portions 25 extend vertically when the locking members 24 are in locking position as illustrated in Fig. 1. On the end of each portion 25 there is formed a handle 26 and in order to hold these rods in their locking 20 positions a suitable lock catch is provided for each rod as indicated at 27.

When the body is raised to its inclined position and it is desired to dump the first or lowermost of the compartments, the tail gate, 25 which is hingedly secured, is released and thus permitted to swing outwardly and allow the material in said compartment to be dumped.

When another equal amount of material 30 is desired the arm 19 holding the lowermost partition is released which is done by first releasing the catch 27 on the rod associated with said arm, then grasping the handle 26 and swinging the bent portion 25 outwardly 35 and downwardly, which in turn rotates the rod and moves the locking member 24 out of the bifurcated end of the arm 19 and thus permits the partition to swing into its dotted line position as shown in Fig. 1, and the 40 contents in the second compartment allowed to dump. The remaining compartments are emptied in a like manner. Any of the rods may be turned and operated by one man, without difficulty.

45 It may also be pointed out that when it is desirable to use the body without the partitions the partitions may be easily removed as before described, and the rods also removed by detaching the locking members 50 24, releasing the catches 27 and then withdrawing the rods from the angle irons in which they are mounted. When all the paraphernalia has been removed it is to be observed that no openings in the body or 55 projections are left to impair the same for its use in other purposes. The fact that no openings are left in the body is a valuable feature in that if the body is desired to be used for hauling sand or the like, such openings would be a decided disadvantage.

While we have shown the preferred form of our invention it will be understood that various changes in the combination, construction and arrangement of parts may be

made by those skilled in the art, without departing from the spirit of the invention as claimed.

Having thus described our invention, what we claim and desire to secure by Letters Patent is:

70 1. In combination, a dump body adapted to be brought to an inclined position, partitions transversely of said body, means for mounting said partitions including a trunnion on each end of said partitions and bearing means therefor, an arm rigidly secured to one trunnion of each partition, means for locking said arms against movement, said means being adapted for individually releasing any of said arms and 75 permit swinging movement thereof.

2. In combination, a dump body adapted to be brought to an inclined position, partitions transversely of said body, means for mounting said partitions including a trunnion on each end of said partitions and bearing means therefor, an arm rigidly secured to one trunnion of each partition, a rod rotatably mounted on the body's side for 80 each of said arms, coacting means on the one end of said rods and said arms whereby the arms are locked against swinging movement, said means being adapted to permit the arms to swing when said rods are rotated to a predetermined point, and means 85 on the other ends of said rods whereby they may be rotated.

3. In combination, a dump body adapted to be brought to an inclined position, partitions transversely of said body, means for 100 mounting said partitions including a trunnion on each end of said partitions and bearing means therefor, an arm rigidly secured to one trunnion of each partition, a rod rotatably mounted on the body's side 105 for each of said arms, coacting means on the one end of said rods and said arms whereby the arms are locked against swinging movement, said means being adapted to permit the arms to swing when said rods are rotated to a predetermined point, means 110 on the other ends of said rods whereby they may be rotated, and means for holding said rods in their locking position.

4. In combination, a dump body adapted 115 to be brought to an inclined position, partitions transversely of said body, means for mounting said partitions including a trunnion on each end of said partitions and bearing means therefor, an arm rigidly secured 120 to one trunnion of each partition, said arms having their opposite end bifurcated, a controlling rod rotatably mounted on the outer side of said body for each of said arms, said rods each having a projecting member 125 extending therefrom and adapted to engage in the bifurcated end of the arm with which it is associated and thereby locking the arm

against movement, and means on the other end of each of said rods whereby they may be individually and manually rotated to bring the projection out of the bifurcated 5 end of the arm with which the rod is associated and permit a swinging movement of said arm.

5. In combination a dump body, partitions transversely of said body, means for 10 mounting said partitions for swinging movement, a rod rotatably mounted on one side of said body for each partition, connecting means between said rods and partition whereby said partitions may be locked 15 against swinging movement; said means being adapted to unlock the partitions and permit swinging movement thereof upon rotation of the rods.

6. In combination a dump body, partitions transversely of said body, means for 20 mounting said partitions for swinging movement, a rod rotatably mounted on one side of said body for each partition, connecting means between said rods and partition 25 whereby said partitions may be locked against swinging movement; said means being adapted to unlock the partitions and

permit swinging movement thereof upon rotation of the rods; and means for turning said rods, and said rods being extended so 30 that they may be operated from a single position.

7. In combination, a dump body, partitions transversely of said body, means for 35 mounting said partitions for swinging movement, a rod rotatably mounted on one side of said body for each partition, connecting means between said rods and partition whereby the partitions may be locked against swinging movement; said connect- 40 ing means being adapted to unlock the partitions and permit swinging movement there- of upon rotation of the rods, and crank means on one end of each rod whereby they may be individually rotated. 45

In testimony whereof we have hereunto set our hands in the presence of two sub-scribing witnesses.
